UNITED STATES PATENT OFFICE.

FREDERICK C. BEAL, OF TORONTO, ONTARIO, CANADA.

SADDLE.

1,155,465.

Specification of Letters Patent.

Patented Oct. 5, 1915.

Application filed March 16, 1915. Serial No. 14,878.

To all whom it may concern:

Be it known that I, FREDERICK C. BEAL, a British subject, residing at the city of Toronto, in the county of York and Province 5 of Ontario, Dominion of Canada, have invented certain new and useful Improvements in Saddles; and I hereby declare that the following is a full, clear, and exact description of the same.

10 This invention relates to certain new and useful improvements in saddles, particularly of that type used for military purposes, the objects of the invention being to so construct the saddle that, regardless of the physical 15 condition of the horse, the withers will not be pinched or pressed upon; there will be no pressure upon the horse's spine; the shoulder bones will have free and uncontrolled movement; and the weight will not be upon 20 the loins but upon the muscles covering the ribs; these being the essential points in the fitting of the saddle for economy of horse flesh.

It is a well established principle in military operations that a cavalry soldier without a horse, or with one that is unfit for service is an encumbrance to his corps, and, for that reason, all thoroughly trained cavalry soldiers are instructed in the proper 30 method of saddling and caring for their mounts, but on the march and particularly during a campaign the muscles of the horse waste away owing to excessive use and to the inability to feed and water at regular periods 35 and consequently it often happens, under these circumstances that a soldier's training in the care of his horse is of very little avail, owing to his inability to procure the means to artificially build up the back to 40 compensate for the wearing away of the muscles and flesh.

Cavalry saddles are required to be placed upon the horse with the front of the saddle sufficiently far back to insure that it does not 45 interfere with the play of the shoulders, and in the case of saddles of the "universal" or "colonial" type the side boards rest flat on the top of the horse's ribs with the front arch clear of the withers to the breadth of 50 not less than two fingers when the rider is in the saddle. With the exercise however of every care to comply with these requirements it is impossible for the rider to maintain the correct position of the saddle on the 55 back when the muscles waste away, owing to the fact that the side boards are fixedly riv-

eted to the arches. Heretofore the arches have been riveted to the side boards and maintained in their spaced relation thereby; suitable webbing being connected to the arches to support the leather forming the seat, with straining webs connected to the side boards and passing transversely across the supporting webs.

To so connect the side boards to the arches 65 that they will automatically adjust themselves to the conformation of the back of the horse regardless of its physical condition is the essential object of this invention, and this is accomplished by pivotally connecting 70 the side boards to the arches so that they can rock in a lateral direction and thus automatically adapt themselves to the curvature or rotundity of the back when placed thereon.

In the drawings: Figure 1, is a perspective view of a saddle tree made in accordance with this invention; Fig. 2, is a front elevation of the same; Fig. 3, is a similar view to Fig. 1, of a modification of the saddle 80 tree shown in that figure; Fig. 4, is a fragmentary perspective view of a modified means of pivoting the side boards to the rear arch; Fig. 5, is a perspective view of the hinges by which the side boards are hinged 85 to the arches; and, Fig. 6, is an inverted perspective view of the hinges shown in Fig. 3.

Like characters of reference refer to like parts throughout the specification and drawings.

In the general construction of the saddle shown in Figs. 1 and 2, I maintain the usual formation of the front arch *b* and rear arch *c* but instead of riveting or otherwise securing these arches to the side boards *a*, as heretofore has been the case, I preferably connect these arches to two spacing boards *a'* which extend from the front arch *b* to the rear arch *c* and hold these arches in their spaced relation.

The side boards *a*, as shown in the accompanying drawings, are similar to those used in the construction of the "universal" military saddle tree, but instead of being rigidly connected to the arches, are hinged or pivoted to the spacing boards *a'*. For this purpose, each side board is provided with two hinge plates *d* formed with hinge members *d'* and passing through the feet of the arches and the spacing boards are the shanks 110 *e* of the hinge lugs *e'*. The hinge lugs *e'* correspond with the hinge members *d'* and

are connected therewith by hinge pins f which pivot the side boards a to the arches so the side boards can rock laterally and automatically adjust themselves to the horse's back.

In that type of saddle in which the webbing is not necessary for the support of the saddle seat, the front and rear arches can be pivoted direct to the side boards, and, in this case, as shown in Fig. 3, each side board is preferably provided with two hinge plates d'' formed with hinge members d' . Each foot c' of the front and rear arches may be of substantially the same shape as its respective hinge plate d'' and is formed with a hinge member, or members c'' corresponding to the hinge members d' , and extending through the hinge members d' and c'' are hinge pins f' by which the side boards are rockably connected to the front and rear arches b and c .

In all cases, the axes of the hinge pins should be in line so that the side boards can rock evenly on their hinge connections with the arches or with the spacing boards and the axis of each D J for the stirrup leathers should also be in line with the axes of the hinge pins, so that the load imparted to the side boards by the stirrup leathers will not disturb the adjustment of the side boards upon the back of the horse.

As shown in Fig. 4, each foot h of the rear arch c may be of a pin formation and is journaled in the hinge members h' of its respective hinge plate h'' , and as in the case of the constructions shown and described

with reference to Figs. 1, 2 and 3, is in line with the corresponding hinge pin for the front arch b .

As shown in Figs. 1 and 2, the front and rear arches are provided with locking devices, such as set screws z , or the like, to hold the side boards in their set position when adjusted to the horse's back.

By means of the foregoing construction, it is possible for the side boards to automatically adjust themselves to the formation of the back, and sit evenly upon the muscles covering the ribs, without pinching or pressing upon the withers or spine, thus leaving the shoulder blade bones free for uncontrolled movement and obviating, or at least reducing to a minimum, the possibility of galling the back during the use of the horse.

What I claim is:

A saddle tree comprising a pair of arches and a pair of spacing members connecting them together and holding them in their spaced relation, in combination with a pair of side-boards, two hinged plates for each side-board, each hinged plate having a set of hinge members, hinge lugs having shanks extending through the feet of the arches, and hinge pins connecting the hinge lugs to the hinge members.

Toronto, February 20th, 1915.

FREDERICK C. BEAL.
